CLAIM

The ornamental design for a footwear as shown and described.

DESCRIPTION

1. Footwear

1.1 : Top

1.2 : Perspective

1.3 : Right

1.4 : Left

1.5 : Front

1.6 : Back

1.7 : Bottom

The representations of the design No. 1 are in greyscale; the design does not claim protection for a specific colouring and/or combination of colours; the representations of the design No. 1 show only the right footwear; the left footwear is omitted as it is symmetrical to the right one.

1 Claim, 7 Drawing Sheets(56)
